US0D1051032S

(12) **United States Design Patent** (10) **Patent No.:** **US D1,051,032 S**
Zheng et al. (45) **Date of Patent:** **** Nov. 12, 2024**

(54) **SNOW CHAIN**

(71) Applicants: **Xiaogen Zheng**, Zhejiang (CN); **Enqi Zheng**, Zhejiang (CN); **Shuxia Ji**, Zhejiang (CN); **Qin Zhou**, Zhejiang (CN); **Rui Peng**, Zhejiang (CN)

(72) Inventors: **Xiaogen Zheng**, Zhejiang (CN); **Enqi Zheng**, Zhejiang (CN); **Shuxia Ji**, Zhejiang (CN); **Qin Zhou**, Zhejiang (CN); **Rui Peng**, Zhejiang (CN)

(**) Term: **15 Years**

(21) Appl. No.: **29/892,561**

(22) Filed: **May 19, 2023**

(51) LOC (14) Cl. **12-15**

(52) U.S. Cl. **D12/608**
USPC ....

Primary Examiner — Michelle E. Wilson

Assistant Examiner — Clese Moore, Jr.

(57) **CLAIM**

The ornamental design for a snow chain as shown and described.

DESCRIPTION

FIG. 1 is a perspective view of a snow chain showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof.

1 Claim, 8 Drawing Sheets
